ELMER E. NEAL, OF NEW HAVEN, CONNECTICUT, ASSIGNOR TO PEERLESS HANDCUFF COMPANY, OF SPRINGFIELD, MASSACHUSETTS, A CORPORATION OF MASSACHUSETTS

LOCK MECHANISM

Application filed October 24, 1929. Serial No. 402,188.

This invention relates to an improvement in lock mechanisms. It is particularly designed for use in handcuff, thumb cuffs, leg irons, or like police officers' means for locking a restraining instrument on prisoners.

I will illustrate the preferred embodiment of the invention in the form of a handcuff of the type in which two arms pivoted to each other make up a prisoner's cuff and with a locking mechanism which permits complete respective rotation of the arms until a wrist is embraced between them and then locks on the wrist because the relative rotation past the lock mechanism can normally occur only in one direction.

One of the principal features of the present invention is to provide novel mechanism for the purpose stated which can be manufactured at a low cost, and to provide such a mechanism with other advantages than the low cost. The various features of the invention will be brought out in the following specification and annexed claims.

In the accompanying drawings—

Fig. 1 is a plan view of one bracelet of a handcuff mechanism such as is usually used in sets of two connected by a chain. The side plate of the lock casing is removed and the locking mechanism shown in place;

Fig. 2 is a detail view of the bolt member which carries the locking roll;

Fig. 3 is a detail view of the pivoted wedge member;

Fig. 4 is a view of the type of key that may be used for lock operation.

As shown, the handcuff consists in two spaced parallel arms 1 and 2 which have a pivot pin 3 connecting them at one pair of adjacent ends and a filler piece 4 between the opposite pair of ends. The locking arm 5 is mounted on pivot pin 3 for complete rotation between arms 1 and 2. The arm 5 has a peripheral arc portion 6 struck from pivot 3 as a center. This arc portion 6 preferably has a smooth surface over which a roller may normally contact with little or no friction. Arm 5 is mounted so the arc 6 may pass over the opening of the lock casing. The latter is formed by filler piece 4, serving as its bottom and end walls and the enlarged

ends of arms 1 and 2 as its side plates. The side plates and filler piece 4 are ordinarily riveted permanently together.

Within the lock casing I provide the U-shaped or yoke member 7 with the two legs 8 and 9 in horizontal position, as shown. The yoke member straddles the key hole 10 of the lock casing. Its upper leg 8 has a roller 12 in bearings at the outer end of the leg. Pivoted in the casing between its side plates is a V-shaped block 13. The lower edge of the block is finished to make surface contact with the inside surface of lower leg 9. The upper block surface is on a slant to act as a wedge and on occasion crowd roller 12 between the wedge and the arc portion 6 of arm 5. A coiled spring 14 mounted in a recess in filler piece 4 normally urges member 7 to the left.

With the construction illustrated, arm 5 may rotate in one direction counterclockwise (as shown) at all times until a wrist or other object is embraced by the arms. In such rotation, spring 14 holds roller 12 in position to contact arc 6 in each rotation. The position of wedge 13 is such that there is enough friction between the arm 5 and the roller to hold the arms against movement until there is force enough to compress spring 14 and release the wedging action. This provides enough friction hold to ordinarily keep the parts in place until movement is desired. After the arms are moved to embrace a wrist, arm 5 cannot be separated from the other arms at the lock casing. Any attempted movement of separation causes a complete wedging movement of roll 12 between block 13 and arc 6 with spring 14 helping. The spring is strong enough to place sufficient friction between the roll surface, block 13 and arm 5, so that any retractive force on the latter wedges the parts more tightly together against all movement in that direction. The block 13 cannot swing out of place with leg 9 lying between its outer end and the bottom of the lock casing. The only thing which can release the mechanism for separation of the arms is to apply force through the key hole to push member 7 back against spring 14 to avoid the wedge. This is accomplished by

the use of the key. The key and key hole are shown in their simplest possible forms, but it should be understood that any of the known arrangements for making it difficult for any instrument except the key to reach through the hole and apply force to a locking part is comprehended in my invention.

It may be desirable to have the line of contact between parts 9 and 13 at a small angle 10 of inclination opposite to the wedge to permit part 13 to drop slightly in the unlocking operation, and I have shown this in the drawings. It should also be understood that member 7 has a loose enough fit in the lock casing 15 to permit the upward wedging movement of roller 12, as described.

It will be clear that my new locking device 20 is not susceptible to lock picking operations in the same way as a ratchet lock on arm 5 would be. And so I do not need to put any anti-picking means to guard the necessary clearance between arm 5 and the top of the lock casing.

The cost of making a lock for my purpose, 25 as shown, is far less than the mechanisms heretofore used for the same purpose. There is nothing to get out of order. And the whole device is particularly adapted for use where a very simple and yet effective handcuff or the like is wanted.

What I claim is:

1. A policeman's cuff for prisoners, comprising relatively rotatable arms to form the cuff, lock mechanism on said arms, a roller 35 and wedge members in said lock mechanism arranged to permit relative rotation of the arms in one direction and wedge the arms against rotation in the other direction.

2. A policeman's cuff for prisoners, comprising relatively rotatable arms to form the cuff, lock mechanism on said arms, a roller and wedge members in said lock mechanism arranged to permit relative rotation of the arms in one direction and wedge the arms 45 against rotation in the other direction, and a spring pressed means to hold said roller and wedge in normally operable position.

3. A policeman's cuff for prisoners, comprising relatively rotatable arms to form the cuff, lock mechanism on said arms, a roller and wedge members in said lock mechanism arranged to permit relative rotation of the arms in one direction and wedge the arms against rotation in the other direction, a 50 spring pressed means to hold said roller and wedge in normally operable position, and a key engageable part on said means for putting said roller and wedge out of relatively operable position.

4. A lock mechanism comprising relatively movable locking arms and lock mechanism having a lock casing on said arms, a roller in said mechanism for engaging one of the arms as it moves past the lock casing means to 60 support said roller and move it from one posi-

tion to another for locking and unlocking operations in said lock casing, and wedging means operable on said roller to bind it into holding engagement with said arm when the roller is moved for its locking operation.

5. In a locking device for application to prisoners, a lock casing having a semi-circular extension, a semi-circular arm pivoted for rotation on the end of said extension, a yoke member having one leg lying adjacent one wall of the lock casing and another leg lying adjacent an opening from the lock casing in the path of said rotatable arm, a roll mounted near the end of said last mentioned leg, a wedge member mounted between said legs, and means to move the yoke member into and out of position to jam the roller between the wedge and the rotatable arm.

6. In a locking device for application to prisoners, a lock casing having a semi-circular extension, a semi-circular arm pivoted for rotation on the end of said extension, a yoke member having one leg lying adjacent one wall of the lock casing and another leg lying adjacent an opening from the lock casing in the path of said rotatable arm, a roll mounted near the end of said last mentioned leg, a wedge member mounted between said legs, and means to move the yoke member into and out of position to jam the roller between the wedge and the rotatable arm, said last named means including a spring normally acting to move the yoke member toward the wedge position.

7. In a locking device for application to prisoners, a lock casing having a semi-circular extension, a semi-circular arm pivoted for rotation on the end of said extension, a yoke member having one leg lying adjacent one wall of the lock casing and another leg lying adjacent an opening from the lock casing in the path of said rotatable arm, a roll mounted near the end of said last mentioned leg, a wedge member mounted between said legs, and means to move the yoke member into and out of position to jam the roller between the wedge and the rotatable arm, said last named means including a spring normally acting to move the yoke member toward the wedge position, said wedge being positioned for the roll to ride up into jamming position in one direction of rotation for said arm and away from said position in the other direction of rotation.

8. In a locking device for application to prisoners, a lock casing having a semi-circular extension, a semi-circular arm pivoted for rotation on the end of said extension, a yoke member having one leg lying adjacent one wall of the lock casing and another leg lying adjacent an opening from the lock casing in the path of said rotatable arm, a roll mounted near the end of said last mentioned leg, a wedge member mounted between said legs, and means to move the yoke member into

and out of position to jam the roller between the wedge and the rotatable arm, said lock casing having a key hole located between said legs to permit the key to reach the part 5 of the yoke connecting the legs to move the latter out of cooperation with the wedge.

9. In a locking device for application to prisoners, comprising two relatively movable arms, a lock casing on one arm having an 10 open wall portion adapted to be closed by a portion of the other arm, lock mechanism in said casing having a roll in said open wall portion adapted to contact the portion of the arm which is adapted to closed said portion, 15 spring pressed means to hold said roll in such contacting position, and a wedge-shaped member underlying said roll to contact therewith and jam the roll against said portion whenever the latter is moved in one direction 20 past said lock casing.

10. A handcuff comprising pivoted arm members arranged for complete relative rotation, a lock casing carried at the free end of one member and having an open wall portion 25 adapted to be closed by the portion of the other member adjacent its free end, and locking mechanism in said casing comprising a wedging device operable out of wedging position by contact with the rotatable arm 30 member when moving in one direction and into wedging position when moving in the opposite direction, said wedging operation acting to direct the thrust of the rotatable arm against the pivot of said arm members.

35 In testimony whereof I have affixed my signature.
